(57) CLAIM

The ornamental design for an article of furniture, as shown and described.

DESCRIPTION

FIG. 1 is a perspective view of the article of furniture embodying the new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The portions shown in phantom lines in FIGS. 1-7 are shown for environmental purposes only and form no part of the claimed design.
